UNITED STATES PATENT OFFICE

2,131,717

LIGHTNING ARRESTER

Edward A. Everett, Long Island City, N. Y.;
 Gustave A. Nelson and William R. Loughridge
 executors of said Edward A. Everett, deceased,
 assigns to E. A. Everett, Inc., Long Island
 City, N. Y., a corporation of New York

Application August 13, 1934, Serial No. 739,638

2 Claims. (Cl. 175—30)

This invention relates to lightning arresters and it has for an object to provide an arrester of the spark gap type in which the elements of the arrester may be assembled and disassembled on an insulated base without varying the sparking relation of these elements. More particularly, the arrester comprises a base of porcelain which is moulded with apertures to receive the attachment of the elements of the arrester including apertures in which dowel pins are accurately secured and by means of these dowel pins the elements of the arrester are maintained accurately in a predetermined sparking relation to each other. The elements may be removed and replaced, or replaced with other elements on the dowel pins without materially changing the relation of the parts.

Other objects of the invention will appear from the following specification and the accompanying drawing, in which:

Fig. 1 is a side elevation of the arrester, partly sectioned;
 Fig. 2 is a top plan view of the arrester;
 Fig. 3 is a sectional elevation on line 3—3 of Fig. 2;
 Fig. 4 is a plan view of the underside of the base;
 Fig. 5 is a template that may be used to space the dowel pins;
 Fig. 6 is a side elevation of one of the discharge blocks;
 Fig. 6a is a plan view of the underside of the discharge block in Fig. 6;

Fig. 7 is a cross-section on an enlarged scale of the porcelain base with the dowel pin cemented in place, and

Fig. 8 is an alternative to Fig. 7 in which the dowel pin is screwed into a metal plug in the base.
 This arrester is of the multi-path type shown in my Patent 1,988,650, of January 22, 1935 and co-pending with the present application. It comprises a porcelain base upon which are mounted a row of discharge blocks connected to the base by binding posts and a discharge plate on each side of said discharge blocks, said discharge plates are also secured to the base by binding posts. It is important to be able to remove and replace the discharge blocks and the discharge plates without changing the discharge relation between these parts.

The porcelain base is made in the usual moulded form with apertures to receive the binding posts. The base is also provided with dowel pins 55 by which the elements of the arrester are proper-

ly spaced. In practice it is not possible to mould dowel pins into porcelain for this purpose and it is therefore necessary to provide an aperture in the porcelain in which the dowel pin is accurately positioned and then secured in position in the aperture by cement or other means. Each part is comparatively loose on the binding post but is provided with at least two dowels by which it is firmly secured in the position desired.

In the drawing, 11 is the porcelain base, 12 is the apertures for the binding posts opening from the bottom, 13 is the binding post at one end for securing discharge plate 14, and 16 is the binding post at the opposite end for securing discharge plate 15 on top of the base. The intermediate binding posts 17 secure the discharge blocks 18 to the base through the top plates 19.

The discharge blocks are centered in a row between the discharge plates 14 and 15 as shown in Fig. 2 and are spaced by an air gap at 20 above the groove 21 formed in the base. Longitudinal grooves are also formed in the base at 24 and 25 below the spark gap discharge points 27 of the plates 14 and 15. These plates have a deep notch at 26 above the transverse grooves 21. This is in accordance with the construction of U. S. Patent 1,714,552, May 28, 1929.

The dowel pins 32 have a collar 33 and a stem 34 loosely mounted in the cavity 36 of the base 11 and secured in position by the cement 35. The pin 32 is smaller than the aperture 41 through which it projects to engage the elements of the arrester. When applied to plates 14 and 15 the dowel pins are threaded to receive the screws 31 to hold the plates in place. The binding post for the discharge block is placed in the aperture 37 and the adjoining apertures 38 are used for the dowel pins which are inserted to register with the apertures 39 and 40. Fig. 6 in the base of the discharge block. It will be noted that the aperture in the base is shouldered or made in two stages and the collar 33 of the dowel is larger in diameter than the top opening but is smaller than the lower opening. The collar rests against the shoulder as the sealing material is poured into the large opening and it prevents the sealing material from entering the small opening.

The plates 14 and 15 are drilled in a fixture to register with the dowel pins and the discharge blocks are drilled at 39 and 40 to register with the dowel pins. These blocks may be made from a variety of materials such, for instance, as is disclosed in U. S. Patent 1,818,184, of August 11, 1931. Where the material can

be accurately moulded the holes 39 and 40 may be formed in the mould.

The dowel pins may be positioned by a template 55, Fig. 5, which is provided with an aperture 37' to receive the binding post and has the holes 51, 52, 53 and 54 properly spaced to receive and position the dowel pins while they are cemented in the base. The holes 51, 52, are for the discharge plates 14 and 15 and the holes 10 53 and 54 are for one of the discharge blocks.

In the construction shown in Fig. 8 the aperture 36 is provided with a metal plug 44 which may be screwed or moulded in place. This plug is drilled by a template for the stem 43 of the 15 dowel 32 which is screwed into the plug and seats on the collar 42. This secures the same results as in Fig. 7.

It is common practice to provide dowel pins in moulded materials like Bakelite which have 20 comparatively little shrinkage and where the metal dowels can be moulded into the stock. This practice is not possible with porcelain which shrinks unevenly and which would fracture if a metal dowel were moulded into the stock. The 25 use of porcelain for a lightning arrester base is highly desirable and the only way to make it practical for present purposes is to locate the dowels loosely in apertures in the porcelain and then secure them in place through plugs which 30 are fixedly located in the apertures.

Having thus described my invention, I claim:

1. A lightning arrester comprising a base of

porcelain having shouldered apertures therein with a dowel pin in each aperture, said pins being of smaller diameter than said apertures and each having a collar engaging the shoulder of the aperture, said pins located in a predetermined fixed relation to each other and cemented in position in said apertures, a discharge block mounted on a pair of said dowel pins and a plate mounted on another pair of said pins in sparking relation to said block and means for 10 connecting a conductor to said block and a conductor to said plate.

2. A lightning arrester comprising a base of porcelain having shouldered apertures therein and with the larger opening of each aperture extending to the base, dowel pins having a collar placed in said apertures, the pins being smaller in diameter than the apertures and the collar being larger in diameter than the upper aperture and smaller in diameter than the lower aperture, 20 said dowel pins being located in a predetermined, fixed relation to each other and secured in position when so located by cement applied to the larger opening of the base, a discharge block engaging a plurality of said pins to accurately position said block on said base, a discharge plate engaging a plurality of said pins to secure the plate in sparking relation to said block, means for securing a conductor to said block and means for securing a conductor to said 30 plate.

EDWARD A. EVERETT.
